UNITED STATES PATENT OFFICE

LEO STEIN, OF NEW YORK, N. Y., AND WILLIAM A. SPARKS, OF HOBOKEN, NEW JERSEY, ASSIGNORS TO THE NATIONAL CASKET COMPANY, OF HOBOKEN, NEW JERSEY.

DESIGN FOR A CASKET.

SPECIFICATION forming part of Design No. 28,112, dated December 28, 1897.

Application filed March 20, 1897. Serial No. 628,532. Term of patent 7 years.

To all whom it may concern:

Be it known that we, LEO STEIN, of New York, in the county of New York, in the State of New York, and WILLIAM A. SPARKS, of Hoboken, in the county of Hudson, in the State of New Jersey, have invented and produced a new and original Design for a Casket, of which the following is a specification, reference being had to the accompanying drawing, showing a part thereof.

The drawing is a perspective view of a casket showing our design.

The leading and essential feature of our design consists of a casket having substantially upright columns at its corners.

The casket A is substantially rectangular in shape, and the columns *a* are substantially rectangular in face view and are formed with

irregular outer faces. Said columns usually extend from substantially the lower edge of the casket to points in proximity to the upper face of said casket.

What we claim is—

The design for a casket, substantially as shown and described.

In testimony whereof we have hereunto signed our names, in the presence of two attesting witnesses, at Hoboken, in the county of Hudson, in the State of New Jersey, this 15th day of March, 1897.

LEO STEIN.
WILLIAM A. SPARKS.
